UNITED STATES PATENT OFFICE.

JENNINGS CROPPER WISE, OF WATERTOWN, NEW YORK.

AGITATING SULFUR-BURNER.

No. 835,926.

Specification of Letters Patent.

Patented Nov. 13, 1906.

Application filed May 12, 1906. Serial No. 316,531.

To all whom it may concern:

Be it known that I, JENNINGS CROPPER WISE, a citizen of the United States, and a resident of Watertown, in the county of Jefferson and State of New York, have invented a new and Improved Agitating Sulfur-Burner, of which the following is a full, clear, and exact description.

My invention relates to sulfur-burners, and mainly to increasing the general efficiency of the same.

Among the several objects of my invention are the following: first, a comparatively large capacity for a given area occupied by the burner; second, the production of a richer and more uniform gas; third, perfect combustion of the sulfur known upon the market as "Louisiana" sulfur; fourth, a saving of labor, due to the fact that the movement of the sulfur into the pot is to some extent automatic; fifth, ease of regulation of the admission of air; and, sixth, uniformity of admission of air into different parts of the burner.

I accomplish these results by certain mechanism shown in the accompanying drawings, described below, and pointed out in the appended claims.

Reference is to be had to the accompanying drawings, forming a part of this specification, in which similar characters of reference indicate corresponding parts in all the figures.

Figure 1 is a side elevation of my burner complete, including the driving mechanism, feed-hopper, air-admission device, and combustion-box. Fig. 2 is a vertical section taken upon the line 2-2 of Fig. 3 looking in the direction of the arrow and showing the revolute stirrer, the feed-hopper, the hand-valves for regulating the feed of sulfur therefrom, and the internal mechanism of the combustion-box. Fig. 3 is a horizontal section through the pot, showing in plan the revolute stirrer and the feed-hopper; and Fig. 4 is a horizontal section through the combustion-box, showing the baffle-plate 61 and its apertures 62.

Upon a surface 5 rest pedestals 6, supporting a pot 7, the general form of which is circular. Depending from this pot 7 are hangers 8, which support a rotatable shaft 9, the outer end of which is provided with a sprocket-wheel 10, suitable for a chain-drive, whereby the shaft is rotated. Collars 11 12 maintain the shaft in proper working relation to the hangers 8. A bevel-pinion 13 is

mounted rigidly upon the inner end of the shaft 9 and rotates therewith. A bevel-gear 14 meshes with the bevel-pinion 13 and is provided with a shoulder 15, which encircles a stem 16. The latter is preferably of steel and is mounted within a pedestal 17, being secured rigidly therein by a set-screw 18. The upper end of the pedestal 17 terminates in a ball-bearing 19, which engages the lower center portion of the shoulder 15, so that the bevel-gear 14 virtually turns upon the ball-bearing. Integral with the bevel-gear 14 and shoulder 15 is a barrel 20, which encircles the stem 16 and is free to turn thereupon. Integral with the pot 7 and encircling the barrel 20 is a bearing-sleeve 21, which projects upwardly. An annular head 22 is secured rigidly to the upper end of the barrel 20 and is provided with arms 23, extending in opposite directions. These arms are provided, respectively, with teeth 24 25, disposed at equal distances from the center represented by the stem 16, the tooth 24 being so disposed relatively to the tooth 25 as to sweep through different paths—that is to say, a tooth 25 does not follow the same path as a tooth 24. The purpose of this arrangement is to render the stirring more thorough.

The pot 7 is provided with a circular aperture 26, normally closed by a circular door 27. Disposed upon opposite sides of this door are lugs 28, supporting a link 29 and connected therewith by means of pins 30. A screw 31 passes vertically through the link 29 and is provided with a head 32, through which passes a hand-lever 33. This arrangement is quite analogous to that employed upon a copying-press. By turning the hand-lever 33 the screw 31 is caused to rotate, and the plate 27 is forced against the under side of the pot 7 or is released therefrom, according to the direction of rotation of the screw. When the screw is so turned as to lower the plate 27, the latter rests upon the upper side of the link 29. The arrangement just described is for the purpose of enabling residual substances and impurities to pass from the pot. The stirrers being constantly at work and the sulfur being gradually burned out, all residual substances gradually assume the form of a powder and find lodgment within the aperture 26, so as to rest upon the plate 27. This plate being lowered, as above described, the powder may be removed as, for instance, by inserting a rake or hoe be-

neath the pot 7, so as to scrap the upper surface of the plate 27. The pot 7 is further provided with horizontally-disposed slots 34, and adjacent to each slot is a movable gate 35, which fits in slideways 36 in vertically-disposed lugs 37. Threaded through each of these lugs for the purpose of holding it in position is a bolt 38, having upon its lower end a revoluble nut 39. The lugs 37 may be removed by merely loosening the nuts 39 and taking out the bolts 38. Each gate 35 is provided with handles 40, whereby it may be raised or lowered, and the gate fits into its slideways with such a degree of tightness that the operator by merely pushing it up or down regulates the virtual capacity or size of the corresponding slot 34.

A flange 41 serves as a limiting-stop for the gates 35. If the slots 34 are to be entirely closed, the gates 35 are merely pushed down into engagement with the flange 41. Another flange 42 is located some distance above the flange 41, and engaging the flange 42 is a flange 43, which is integral with a dome 44.

A number of feed-holes through the pot are shown at 45 and are spaced equidistant. Adjacent to each of these feed-holes is a conical valve 46, mounted rigidly upon the end 30 of a revoluble screw 47, provided at its outer end with a hand-wheel 48. By turning the hand-wheel 48 the conical valve 46 is brought partially into the corresponding feed-hole 45 and may be made to close the same to any desired extent. In order, therefore, to regulate the capacity of the feed-holes, all that is necessary is to turn the hand-wheel 48.

The dome 44 is provided with a neck 49, terminating in a flange 50, which engages a flange 51 of another neck 52. Mounted upon the neck last mentioned is a combustion-box 53. The latter is of cylindrical shape and is provided with slideways 54. The ends of the combustion-box 53 are disks 45 or heads 55, each being provided with a spider 56, supporting a revoluble damper 57. By turning this damper the interior of the combustion-box may to a greater or lesser extent be brought into communication with the outer atmosphere. Bolts 58 59 secure one of the heads 55 in position. The other head is mounted upon a hinge 60 and bolts 59. By removing the latter this head (represented at the right of Fig. 4) may be swung open.

Mounted in slideways 54 and inclosed by the combustion-box 53 is a baffle-plate 61, provided at its opposite ends with apertures 62, as will be understood from Fig. 4. This baffle-plate may be removed by sliding it out endwise, one or the other of the heads 55, preferably the one shown at the right of Fig. 4, being first moved out of the way.

Doors 63, mounted upon hinges 64, are employed for the purpose of giving access to

the interior of the apparatus. Superposed above the combustion-box 53 is a neck 65, and adjustably mounted within this neck is a damper 66, supported by a stem 67. By turning the latter by hand the damper 66 7c may be tilted to any desired angle, and thus caused to check the outflow of gas from the burner. The neck 65 terminates in a flange 68 for enabling the apparatus to be connected with a cooler of the style commonly used 75 in this art. A hopper is shown at 69 and is used for supplying sulfur to the pot.

The operation of my device is as follows: Sulfur of almost any kind—for instance, the so-called "Louisiana" sulfur—is placed with- 80 in the hopper 69 and is melted by heat from the interior of the pot, as hereinafter described. The molten sulfur seeks to finds its way through the feed-holes 45, and the ca- 85 pacity of these holes, as above explained, is regulated by turning the hand-wheel 48 into appropriate position. The sulfur is thus gradually fed down into the pot, where it ap- 90 pears as a liquid. Power being now applied to the sprocket-wheel 10, the stirrer 23 is ro- 95 tated and the teeth 24 25 pass circularly around the bearing-sleeve 21. As each tooth describes a path independent of the other path the stirring is rendered thorough. After a long use any residual powder which may 100 accumulate in the pot is removed through the aperture 26, as above described. The sulfur within the pot is ignited and tends to burn after the manner of other combustibles.

The supply of air through the slots 34 is reg- 105 ulated to a nicety by adjusting the positions of the several gates 35. The exact position to be occupied by these gates in order to supply a proper degree of air is somewhat arbitrary, depending upon the quality of the sulfur, the 110 general temperature of the air where the apparatus is being used, the size of the apparatus, the force exerted by the suction-pump in drawing gases out of the apparatus, and many other factors. The quantity of air 115 supplied to the burning sulfur is such as to form sulfur dioxid, (SO₂) which is employed in making sulfit liquor. As the gas passes upward in the combustion-box 53 it en- 120 counters the baffle-plate 61 and is forced to divide so as to pass through the two aper- 125 tures 62, as will be understood from Fig. 4. The two portions of gas thus separated im- 130 mediately recombine in the upper part of the combustion-chamber. The dampers 57 if 135 turned to a proper angle admit sufficient air to prevent sublimation. I find that in some instances it is desirable to admit a supply of air directly in the combustion-box independ- 140 ently of the supply of air through the slots 34. It is upon this account that I employ the two dampers 57. By turning these dampers to any desired extent a corresponding amount of air is caused to enter through the 145 heads of the combustion-box. This auxil- 150

ary admission of air is desirable when for any reason difficulty is encountered in causing thorough combustion within the pot, and consequently there is a tendency for the unburned sulfur vapors or sublimed portions of the sulfur to pass off in elementary form. I find that if air be admitted through the heads of the combustion-box, as above described, it will cause any unburned sulfur vapors or sublimated portions of sulfur to burn and form SO_2 , provided the aeroform portions just mentioned have sufficient heat. It should be borne in mind that notwithstanding the endosmotic proportion of gases and vapors it may sometimes happen, especially in a rapidly-working apparatus, that some portion of sulfur vapor does not happen to be brought into contact with a proportionate quantity of air, and while possessing sufficient heat to support combustion is prevented from being consumed upon this account. In such instance the auxiliary air-inlets are useful. The dampers and baffle-plates are essential to thorough combustion.

I desire to lay emphasis upon the fact that the general form of the pot is circular and that the slots 34 are therefore arranged in the form of a circle and are equidistant from the center of the pot. By this arrangement the several distinct volumes of air passing inward radially through the different slots toward the center of the burner must travel equal distances and are therefore exposed to like conditions. The tendency, therefore, is to produce uniformity in the conditions existing throughout the pot and to promote the uniform combustion of the sulfur vapor as far as practicable. I have found from actual trial that the circular form given to the pot increases the general efficiency of the apparatus to a degree which is astonishing. The better results are, no doubt, attributable to the fact that perfect burning of the sulfur is obtained because of the equality of the several drafts taking place in different directions. Moreover, because of the fact that the several drafts converge toward the center of the pot the admixture of the air and gas is rendered more thorough than would be the case if a cubular pot were employed.

The machine above described may be employed for many purposes other than that described. I therefore do not limit myself to any particular service to which it may be applied; neither do I limit myself to the particular mechanism shown.

Having thus described my invention, I claim as new and desire to secure by Letters Patent—

1. The combination of a vessel provided with feed-holes, manually-operated valves for limiting the capacity of said feed-holes, a hopper for supplying melted sulfur through said feed-holes, mechanism mounted within

said vessel for agitating said sulfur as the same is burned therein, and means for removing gases formed by combustion of said sulfur.

2. In a sulfur-burner, the combination of a vessel for containing burning sulfur, a combustion-chamber in connection with said vessel and provided with slideways, a baffle-plate mounted within said slideways and provided at its opposite edges with apertures, and means for regulating the flow of the gases of combustion around said baffle-plate.

3. In a sulfur-burner, the combination of a vessel for containing burning sulfur, a combustion-box communicating with said vessel, a baffle-plate mounted within said combustion-box, and means for admitting air immediately above and immediately below said baffle-plate.

4. In a sulfur-burner, the combination of a vessel provided with an aperture for containing burning sulfur, means for agitating burning sulfur, means for forcing into said aperture residual substances liberated by the combustion of said sulfur, a plate for closing said aperture, and means controllable at will for removing said plate in order to dislodge said residual substances.

5. In a sulfur-burner, the combination of a vessel for containing burning sulfur, said vessel being provided with an aperture, means for agitating said burning sulfur within said vessel so as to liberate therefrom residual substances and to force the latter into said aperture, a plate for normally closing said aperture, and a hand-operated screw for holding the said plate against said aperture.

6. In a sulfur-burner, the combination of a pot provided with a central bearing-sleeve, a stirrer mounted within said pot and revolvable in relation thereto, mechanism connected with said stirrer for turning the same, and a hopper concentric to said pot for supplying sulfur thereto.

7. The combination of a containing vessel for burning sulfur, a hopper partially encircling said containing vessel and disposed concentric thereto, means for feeding sulfur from said hopper into said containing vessel, and mechanism for conducting away the gases of combustion of said sulfur.

8. The combination of a containing vessel for burning sulfur, a hopper partially encircling said containing vessel and concentric thereto for supplying sulfur thereinto, said hopper being immediately adjacent to said containing vessel so that said sulfur within said hopper may be melted by heat from said containing vessel, and means for regulating the supply of sulfur from said hopper into said containing vessel.

9. In a sulfur-burner, the combination of a circular vessel for containing burning sulfur, a hopper partially encircling said vessel and adapted to hold melted sulfur, and mechan-

65 70 75 80 85 90 95 100 105 110 115 120 125 130

ism for controlling the flow of said sulfur from said hopper into said vessel.

10. The combination of a containing vessel, a hopper partially encircling the same, 5 means for controlling a flow of sulfur from said hopper to said containing vessel, a plurality of gates disposed below said hopper and adapted to admit a supply of air radially toward the center of said containing vessel, a 10 stirrer mounted within said containing vessel, and means for actuating said stirrer.

11. The combination of a receptacle for burning sulfur, a combustion-chamber con-

municating with said vessel, a baffle-plate 15 slidably mounted within said combustion-chamber and provided with apertures, and a closure member mounted upon said combustion-chamber at a point adjacent to said baffle-plate.

In testimony whereof I have signed my 20 name to this specification in the presence of two subscribing witnesses.

JENNINGS CROPPER WISE.
